CLAIM

The ornamental design for a golf putter head, as shown and described.

DESCRIPTION

FIG. 1 is a front view in perspective of a golf putter head embodying my new design;

FIG. 2 is a heel end view, thereof;

FIG. 3 is a rear elevational view, thereof;

FIG. 4 is a toe end view, thereof;

FIG. 5 is a top view, thereof; and,

FIG. 6 is a rear view in perspective showing a modified embodiment of my new design.

The undisclosed sides of the second embodiment are identical to those disclosed in the first embodiment.
